UNITED STATES PATENT OFFICE

FRIEDRICH MULKA, OF SUHL, GERMANY

ATTACHMENT FOR TURNING WORK PIECES BY MEANS OF BROAD CUTTERS

Application filed July 2, 1928, Serial No. 289,834, and in Germany July 6, 1927.

The present invention relates to a process for turning work-pieces by means of broad cutters. The novelty and fundamental subject of the invention consists therein, that in themselves known broad cutters are connected in groups and that the individual broad cutters of a group are acting upon equal length of the work-piece, respectively take off chips of equal width. In order, that the 10 acting forces may be compensated reciprocally, the broad cutters of one group are so arranged, that their center-lines are located exactly, or approximately so, in one plane. It is hereby enabled to take off a considerably 15 greater chip-cross-section under equal cutting-velocity. By this process, work can on an average be done in one tenth of the time hitherto required and the increase in capacity is therefore extraordinarily great. It is 20 but natural, that the piece of metal can simultaneously be worked by a number of groups of broad cutters to enable working upon greater length. According to the present invention, the broad cutters are only moving radially. Under such radial movement 25 is however not only understood the absolutely rectilinear movement from the periphery towards the center, but all oscillating motions of the work-piece from outward to the 30 inward, even though these movements may not be perfectly rectilinear.

The technical progress of the process consists therein, that oscillations can not arise even with excessively broad chips and that the turning-tool can be moved with the same feeding-velocity employed in longitudinal turning for roughing. Oscillation can not arise, as the tools, acting from all sides upon the work-piece, prevent a deflection of the 40 work-piece under the feeding-pressure and that the force of the cutting-pressure, having a tendency to produce oscillations, can not become effective, as several, different chip-cross-sections are turned off simultaneously, so that in a part of the turning-tools

an increase in cutting-pressure and in another part of the turning-tools a decrease in the cutting-pressure is being produced. These periodical, reciprocal effects arise consequent to the separation of different chip-cross-sections. 50

A feeding-velocity, as in longitudinal turning, can, according to the present invention be obtained by means of cross-cutters for the reason, that different tools work in different planes and are consequently working without lateral friction and free from oscillations. 55

The considerable saving of time, or the considerable increase in capacity under 60 equal consumption of time, is based thereupon, that considerably larger chip-cross-sections can be taken off, than would be possible according to the known process, even under most economical working. 65

An idea of the capacity of a lathe is formed by the ratio of: feeding-distance to length of turning. While in turning with a turning-tool, moved in the longitudinal direction of the work-piece, the greatest depth of cut 70 is, under most favourable conditions equal to work-piece-diameter minus diameter of the piece to be turned-on, divided by two and while the feeding-distance must correspond to the length of turning, the width 75 of cut can, by the novel process, be equal to a multiple of the work-piece-diameter, i. e. in many instances equal to the length of turning, while the feeding-distance will in all cases only be: work-piece-diameter minus 80 diameter of piece to be turned-on, divided by two. The increase in capacity of the lathe under employment of the present process can consequently be expressed as follows: length to be turned divided by work-piece-diameter, 85 minus piece-diameter to be turned, divided by two.

If it is a question of taking off a chip of 3 mm. thickness for a length to be turned of 30 mm., the feeding-distance is, accord- 90

ing to the above arguments in the known process 30 mm., in the new process however only 3 mm., so that an increased capacity of $30 : 3 = 10$ is obtained, i. e. only one tenth 5 part of the time is required, or ten times the length can be turned in the same time by working in accordance with the novel process. Hereby it is naturally supposed, that the employed cutters are having a total width 10 of 30 mm. and that the feeding-velocity is in both cases equal.

This increase in capacity obtained under equal number of revolutions of the work-piece during working, can considerably be 15 increased thereby, that the number of revolutions of the work-piece is increased at the ratio, in which the diameter of the work-piece is being reduced during working, so that the highest cutting-velocity is always 20 maintained.

Another considerable advantage of the new process consists therein, that the specific consumption of power is smaller as in the hitherto known process for the reason, that 25 the feeding-pressure and the cutting-pressure are not straining the spindle of the lathe. In turning by means of tools moved in longitudinal direction, the longitudinal bearing is loaded by the feeding-pressure 30 and the cross-bearing of the lathe-spindle by the main cutting-pressure.

Devices for the novel process are illustrated schematically in the accompanying drawings.

35 Fig. 1 is an end-view of the face-plate carrying the turning-tools and the bar of material to be turned.

Fig. 2 is a side-elevation of Fig. 1.

Fig. 3 shows the manufacture of a cylindrical pivot.

40 Figs. 4, 4a and 4b show the arrangement of two groups of broad cutters, wherein the broad cutters are staggered by 180° .

Figs. 5 and 5a show one embodiment of the 45 invention relative to the arrangement of tools, with three broad cutters.

Fig. 6, 6a and 6b show constructions modified compared with the construction according to Fig. 1.

50 Fig. 7 shows an arrangement with auxiliary supports.

On the face-plate *a*, four tools, *b*, *c*, *d*, and *e* are f. i. provided. The rod *f* of the material to be worked, is passed through the face-plate 55 *a*. The turning-tools *b*, *c*, *d* and *e* are moved vertical to the axis of the revolving work-piece *f*. The turning-tools *b* and *d* are employed for roughing the grooves *g*. These tools are provided with two teeth *b'* respectively *d'*. The tools *c* and *e* serve for taking off the remaining parts *h* from the work-piece. The tools *b* and *d* commence and finish the work by one to two revolutions of the work-piece earlier, than tools *c* and *e* use for 60 the finishing cut.

In the tools *b* and *d*, a comparatively small lateral pressure arises during working at the ends of the teeth *b'*, as the same can be designed oblique and as the depth of cut, amounting to only 1 to $1\frac{1}{2}$ feed depth per 70 revolution, remains constant.

Dividing the chip according to Fig. 3 enables, that the left hand tooth of the tool *b* cuts with both edges, while the right hand tooth of the tool *b* and the teeth of the tool *d* are cutting with one edge only. The tools *c* and *e* however are working perfectly unobstructed, as they are only separating the ribs *h*.

80 The constructions, embodying the process according to Figs. 4-7, show groups of broad cutters, whereby the steel is worked symmetric and concentric. This has the advantage, that the work-piece is acted upon by the broad cutters from all sides, so that the work-piece centers itself automatically between the broad cutters. A torsional strain is consequently only exerted upon the work-piece and working can therefore be done with comparatively very broad cutters.

90 In Fig. 4 working is effected for a certain length by two groups staggered by 90° , wherefrom each two opposite disposed broad cutters belong to one group. Corresponding thereto, the broad cutters *b* and *c* belong f. i. to the first group and the broad cutters *d* and *e* to the second group. The broad cutters *b* and *c* are staggered in one plane *d*-*d* by 180° . The broad cutters *d* and *e* are disposed in a second plane *B*-*B*, staggered by 180° , the said plane being twisted compared to the plane *A*-*A*, by 90° . The center-line *I*-*II* of the group of broad cutters *b*, *c* can be staggered, relative to the center-line *III*-*IV* of the group of broad cutters *d*, *e*.

100 In Fig. 5, working of a certain length is effected by one group of three broad cutters belonging together, being each staggered to one-another by 120° . Fig. 5a shows in what manner the working-breadth of the individual cutters are staggered towards each other.

110 Fig. 6 shows the working by one group of four broad cutters, belonging together, staggered by 90° each.

115 Fig. 7 shows working of a greater breadth with two broad cutters only, staggered towards each other by 180° . The broad cutter 1 is designed as multiple-tool cutter, the broad cutter 2 preferably as solid cutter. To prevent fluctuations in the work-piece, two supports, *f* and *g*, staggered towards each other by 180° , are f. i. designed as rollers and simultaneously fed forward radially with the broad cutters. This construction has the advantage, that only two broad cutters are required for working one length to be turned. In all the illustrated arrangements, equal length, respectively equal chip-cross-sections are separated by the broad cutters belonging together. The feeding-pressure, according 120 125 130

to Fig. 7, is hereby f. i. compensated in radial direction and the main cutting-pressure in vertical direction. Dividing the width of chips enables generally in everyone of the multiple cutting-edges to convert the oscillating forces of the cutting-pressure into a constant force.

It has been proved particularly practical, to make the individual edges of the multiple cutters of different width, so that these individual edges are taking off differently large chip-cross-sections.

Different values of oscillations are hereby produced by the cutting-pressure of the various edges, whereby the total pressure of all cutting-edges exerts itself with greatest certainty as constant force upon the work-piece. The total chip-cross-section, taken off by the multiple cutter is hereby likewise the same as the chip-cross-section taken off by the solid cutter belonging thereto.

In all the illustrated arrangements the broad cutters, belonging together, separate equal length, respectively equal chip-cross-sections.

A special advantage of the present mode of embodying the invention consists therein, that one broad cutter each of a group is provided with an uninterrupted cutting-edge, as f. i. in Fig. 4 the cutters *c* and *e*, in Fig. 5 the cutter *b*, in Fig. 6, the cutter *e*. These cutters, with a full edge, are, during roughing of the broad cutters disposed in front thereof, only taking the remaining equal chip-cross-section off, like the other multiple broad cutters belonging thereto. After completion of the roughing-work by the multiple cutters, the same act, during 2-3 revolutions of the work-piece, as scrapers and produce thereby an extraordinary smooth working-surface, such as could otherwise only be obtained in present machine tools by grinding.

The above described invention can be varied within wide limits without impairing the range of the invention in itself thereby. The abstraction, width of cut, or width of chip may f. i. be considered identical, if the cutter *c* is f. i. of greater width as the distance between *b' b'*, as the cutter *c* is in this case only taking off the remaining width of chip, even if the cutter *c* should itself be of greater width. In the claims, the expression "effective width of chip" has consequently been used as general characteristics. It is likewise possible to provide the cutter *c* likewise with two edges *c' c'*, whereby the total of the prongs *b' b'* should be equal to the total of the prongs *c' c'*. In this instance, it is possible, that the one prong *c'* will be located between the two prongs *b' b'* and the centre-lines of *b* and *c* would in this case not coincide perfectly, but be displaced towards one-another by half the width of tooth *b'* or

c'. These and similar constructions shall be understood as covered by the claims.

I claim:

1. A turning attachment comprising a plurality of radially movable broad cutters symmetrically arranged around the work-piece, each of which cutters is adapted to take off an equal chip cross-section from the said work-piece and be simultaneously moved radially with the same velocity during the cutting operation. 70

2. A turning attachment comprising a plurality of radially movable broad cutters forming a group, which cutters are symmetrically arranged in one plane vertical to the axis of and around the work-piece, and each of which is adapted to take off equal chip-cross-sections from the said work-piece, said cutters having an equal and simultaneous radial movement during cutting operation. 80

3. A turning attachment comprising a plurality of group cutters, each containing plural radially movable broad cutters, the cutters of one group being symmetrically arranged so as to exert their cutting force in one plane vertical to the axis of and around the work-piece, the cutter groups being arranged one after another lengthwise to the axis of the work-piece, said cutters being radially movable during the cutting operation. 90

4. A turning attachment comprising a plurality of radially movable broad cutters symmetrically arranged in groups around the work-piece, each of which broad cutters comprises a plurality of cutting teeth, which teeth of a single cutter are displaced symmetrically to the teeth of the other broad cutters of the same group, said cutters being radially movable during the cutting operation. 100

5. A turning attachment comprising a plurality of radially movable broad cutters symmetrically arranged in groups around the work-piece, certain of which broad cutters comprise a series of cutting teeth of different width, the total width of which is equal to the total width of each other broad cutter belonging to the same group, said cutters being radially movable during the cutting operation. 110

6. A turning attachment comprising a plurality of cutters arranged symmetrically about the work-piece, said cutters being adapted to be moved radially of the work-piece, the cutting edge of one cutter being composed of a plurality of unequal width teeth, and the cutting edge of its opposed cutter being continuous, the effective cutting edges of the respective cutters being adapted to remove equal chip-cross-sections from the work-piece, said cutters being radially movable during the cutting operation. 120

7. A turning attachment comprising a plurality of broad cutters symmetrically 130

disposed about the work-piece, said cutters extending the full length of the work-piece and adapted to be radially moved with respect to the said work-piece, certain of said cutters having a plurality of cutting edges of unequal widths tending to break up the turning oscillations produced by the cutters into oscillations of unequal frequencies counteracting each other whereby to increase the cutting stability, and said cutters being radially movable during the cutting operation.

In testimony whereof I have affixed my signature.

FRIEDRICH MULKA.
